UNITED STATES PATENT OFFICE.

JOHN GASPARI, OF NEW YORK, N. Y., ASSIGNOR TO DE LUXE OPTICAL CO. INC., OF NEW YORK, N. Y., A CORPORATION OF NEW YORK.

DESIGN FOR AN EYEGLASS FRAME.

Application filed April 6, 1927. Serial No. 21,495. Term of patent 14 years.

To all whom it may concern:

Be it known that I, JOHN GASPARI, a subject of Italy, residing at New York, county of New York, and State of New York, have invented a new, original, and ornamental Design for Eyeglass Frames, of which the following is a specification, reference being had to the accompanying drawing, forming part thereof.

Fig. 1 is a front view.

Fig. 2 is a top plan.

Fig. 3 is an end view.

The invention resides in the shape of the lens frames which are designed to accommodate a wide, spring bridge whereby a substantially uniform and regular elliptical shaped frame is presented.

I claim:

The ornamental design for an eyeglass frame as shown and described.

JOHN GASPARI.
